UNITED STATES PATENT OFFICE

2,327,441

DOOR LOCK

William Marshall, Detroit, Mich., assignor to
 Briggs Manufacturing Company, Detroit, Mich.,
 a corporation of Michigan

Application October 22, 1941, Serial No. 416,012

9 Claims. (Cl. 292—220)

This invention relates to door latches or door latch assemblies and particularly, although not exclusively, to combination dovetails and latch devices adapted for use in connection with the doors of motor vehicles and the like. The invention contemplates the provision of an improved device of this class adapted to be installed upon the swinging door of the vehicle body.

One of the objects of the present invention is to provide an improved device of the foregoing character in which the latch assembly is so mounted with relation to the door that the latch extends transversely thereof.

Another object of the present invention is to provide an improved device of the foregoing character which affords two latching positions for the door to which the device is applied.

A further object of the present invention is to provide an improved device of the foregoing character in which the latch member is combined with a wedging element or dovetail, both thereof being mounted to extend transversely of the door.

A further object of the present invention is to provide an improved device of the foregoing character in which the combined wedging element or dovetail and the latch are adapted to engage vertically spaced striker elements carried by the door jamb.

Another object of the present invention is to provide an improved combined wedging element or dovetail and latch assembly in which the wedging element or dovetail may be manually adjusted to take care of any variation or tolerances between the vehicle door and its jamb or to take up variations due to wear.

A further object of the invention is to provide an improved device of the foregoing character in which the latch member is combined with and forms a movable part of a wedging element or dovetail structure.

Another object of the invention is to provide an improved device of the foregoing character in which an oscillatable latch member forms a part of a wedging element or dovetail structure and one in which the wedging element or dovetail structure may be adjusted with relation to the striker device after installation upon the vehicle door.

A further object of the present invention is to provide an improved latch structure having a control lever or link operable by means of the door handle or by means of a remote control device and engageable with the latch member for retracting the same.

Another object of the present invention is to provide a device of the foregoing structure which is of relatively simple construction, comprising a minimum of parts, and one which can be manufactured at relatively low cost.

A further object of the present invention is to provide an improved latch assembly of the foregoing character which includes a rollback or actuating device and a control lever or link in which the control lever or link is interposed between the rollback and the latch and is engageable with the latter for retracting the same upon operation of the door handle and/or the actuation of a remote control handle located on the inner side of the vehicle door.

Another object of the present invention is to provide a device of the foregoing character in the form of a combined wedging member or dovetail and a latch member.

15 A further object of the invention is to provide an improved device of the foregoing character in which there is provided a combined wedging member or dovetail and a latch member in which the combined structure is located so as to be disposed transversely of the vehicle door.

Another object of the present invention is to provide a combined wedging member or dovetail and a latch member in which the wedging member or dovetail is provided with a depression or socket portion and in which a pivoted latch member is associated with the wedging member or dovetail and is normally in projected position with relation to the socket but which is capable of being retracted into said socket.

20 Another object of the invention is to provide improved latching or locking mechanism for a vehicle door in which said mechanism includes a striker device of improved nature.

The above and other objects and advantages will appear from the following description and appended claims when considered in connection with the accompanying drawings forming a part of this specification wherein like reference characters designate corresponding parts in the several views.

In said drawings:

Fig. 1 is a fragmentary side elevation of a portion of a motor vehicle body in which the present invention is incorporated in connection with a rear door thereof.

Fig. 2 is an enlarged fragmentary sectional view taken substantially along the line 2—2 of Fig. 1, looking in the direction of the arrows.

Fig. 3 is an enlarged perspective view, partly broken away for purposes of clarity, of the latch mechanism and associated parts embodying the present invention.

Fig. 4 is a fragmentary detail sectional view, partly in elevation, taken substantially along the line 4—4 of Fig. 2, looking in the direction of the arrows.

Fig. 5 is a detail perspective view of a striker device embodying the present invention.

Fig. 6 is an elevational view of the structure.

shown in Fig. 3 and illustrating the locked and released positions of the parts.

Fig. 7 is a fragmentary sectional view taken substantially along the line 7—7 of Fig. 6, looking in the direction of the arrows; and

Fig. 8 is an enlarged fragmentary elevational view of the mounting means for one end or portion of the remote control locking device for locking and releasing the latch mechanism of the preceding views.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

Referring now particularly to the drawings, and especially Fig. 1 thereof, A represents as a whole a portion of a motor vehicle body of the enclosed type which is provided with a rear door B and a front door C. The rear door is of the type which is hinged at its forward edge to a body pillar or post which is located between the front and rear doors.

The improved door latch assembly embodying the present invention is indicated as a whole at D in Figs. 1 and 3, and as shown in Fig. 1, is incorporated with the rear door B. The latch bolt assembly or mechanism D is adapted to be operated or actuated from outside the door B by means of the usual handle E and is also adapted to be operated from the interior or inner side of the door B by means of a remote control device, shown as a whole at F.

The front door C of the body illustrated in Fig. 1 may be provided with a key actuated latch mechanism which is shown as a whole at G, this mechanism being similar to that shown at D. The latch mechanism G is, as shown, provided with an external actuating handle H and with an interior remote control device which is provided with a handle K.

While I have shown my improved latch assembly or mechanism embodying the present invention, merely for purposes of illustration, as being applied to the doors B and C which are hinged at their front edges, it will be understood, of course, that the latch mechanism or assembly is equally well adapted for use upon doors which are hinged at their opposite or rear edges.

Referring particularly to Figs. 3 and 6 of the drawings, the latch assembly or mechanism D, as shown, comprises a suitable upright case or mounting plate 10 having an end flange 11 which extends at substantially a right angle to the main or base portion 10 of the case plate. The flange 11, as shown, is provided with a pair of spaced apertured embossments 12 on its inner face and the main portion of the case plate 10, with similar apertured embossments 13, two such embossments being shown.

The latch assembly of the present invention comprises a latch actuator or rollback device, shown as a whole at 14, said device being mounted upon the inner face of the case plate 10 by means of a round or circular rearward projection or embossment 14a which is adapted to be journaled in a similarly shaped hole or opening in the case plate portion 10 (see particularly Fig.

7) so that the actuator or rollback may be oscillated or swung from its full line position, shown in Figs. 3 and 6, to its broken line position shown in Fig. 6. The embossment 14a is provided with a square opening or socket 14b, see particularly Fig. 3. As shown, the actuator or rollback 14 is of substantially triangular shape or formation and is provided with an upright straight edge portion 15 and a straight edged heel portion 16 which normally contacts the inner face of the flange 11 when the rollback is in its vertical or full line position, as seen in Figs. 3 and 6. The upper inner portion of the rollback 14 is provided with a notch or horizontal slot 17 and with an overhanging nose or substantially hook-like portion 18.

An actuating lever or link member, shown as a whole at 20, is pivotally mounted upon the inner face of the case plate portion 10 by means of a pivot pin or stud 21. This actuating lever or intermediate control member 20 is provided with an upright leg portion 22 which extends substantially parallel to the plane of the case plate portion 10 and with a lower offset or angularly disposed portion 25 which extends in a plane which is substantially parallel to the plane of the flange 11. The upright portion 22 of the lever converges slightly toward its upper end and its inner and outer edges 23 and 24, respectively, are straight. The edge 23 is adapted to contact the adjacent edge 15 of the rollback device in flat-wise relation when the latch member and parts are in the positions in which they are shown in full lines in Figs. 3 and 6. The offset lower portion 25 of the lever is provided with an upper edge portion 26 which is also flat and which is adapted to contact an offset portion or projecting pin extending from the latch element, as will be described fully hereinafter.

The latch member or element, see particularly Fig. 4, is maintained in its projected position as therein shown by a tension spring and the rollback device 14 and lever 20 are normally maintained in the positions in which they are shown in Fig. 3 by means of a flat coiled tension spring 30. As shown, one end of the spring 30 is held by a substantially U-shaped clip or support 31 carried by the plate 10. The spring is coiled and extends upwardly toward the rollback 14 contacting lever 20 with its upper or free end 32 having a pressure contact with the edge 24 of the lever 20. The spring 30 is of sufficient strength to maintain the lever 20 and the rollback 14 normally in their upright positions, yet permitting them to be operated by the outside door handle E or the remote control device F to retract and thus release the latch from locking or latching position.

Referring now particularly to Fig. 4, the latch device or mechanism of the present invention is, as shown, in the form of a combined dovetail or wedging element and a pivoted latch member or element. This combined structure is mounted upon the outer face of the flange 11 and extends, when the assembly is attached to the vehicle door B, transversely of said door. The wedging member or dovetail of the latch mechanism is larger at its forward or outer end adjacent the outer edge of the flange 11 than at its inner end in the direction of the base portion 10 of the mounting or case plate. The latch device is shown as a whole at 35 and comprises the wedge-shaped body portion or dovetail member 36 having a flat upright outer face 37 and a rearwardly and downwardly tapering top wall 38 and a rear-

wardly and upwardly tapering lower or bottom wall 39. The body member 36 is attached to the flange 11 in any suitable manner (not shown) so as to be rigidly mounted upon said flange. As stated above, the body member 36 is of wedge-like formation, and has a rounded inner end or nose portion 49 which is substantially flush with the back face of the case plate portion 10.

As best seen in Fig. 4, the under portion or wall 39 of the wedge-shaped body member 36 is provided with a longitudinally extending recess or socket 41 within which the latch member or element shown as a whole at 42, is pivotally mounted upon a pin or stud 43. The under face of the body member 36 is provided with a transverse slot 48 which registers with a similar slot 49 formed in the flange 11, see Fig. 3. The latch member or element 42 carries a transversely projecting pin or stud member 46 which extends through the slots 48 and 49 and projects inwardly beyond the inner face of the flange 11, see particularly Figs. 3, 6 and 7.

The latch member or element 42 is provided with a flat and straight free end portion 42a and is notched in its lower face adjacent said end portion to provide an abutment or shoulder 42b. These portions 42a and 42b of the latch element are adapted to engage a striker member as will be presently described.

The body portion 36 of the combined wedge and latch structure is drilled in a vertical direction so as to provide a threaded socket for an adjustable screw member or stud 44. The upper or top edge 38 of the wedge member or dovetail is provided with a spring-like metal plate or cover 45 which is held in position by a screw or the like 45a. The free end of the member 45 is flanged or turned down at 47 to overlie the adjacent face or wall 37 of the wedge member. It will be seen that by adjusting the screw or threaded stud 44, the position of the member or plate 45 with relation to the upper surface or edge 38 of the dovetail can be varied. The purpose of this structure is to provide for relatively fine adjustments so as to take care of any variations or tolerances between the latch device carried by the door and the striker device carried by the door pillar or jamb. By providing such means for adjustment, the door to which the latch mechanism of the present invention is applied may be kept from rattling and jarring.

The latch member or element 42 is normally maintained in its projected position as seen in Fig. 4 by means of a tension spring 50 whose upper end is wrapped or coiled around an inwardly projecting pin or stud 51 carried by the flange 11 and whose lower end engages the pin 46 carried by the latch element. To prevent the tension spring 50 from becoming released from the stud or pin 51, a cotter pin or the like 52 is passed through a transverse slot or opening formed in the stud or member 51.

As best seen in Fig. 5, an improved striker device embodying the present invention is shown as a whole at 55. This device comprises a base plate 56 having spaced holes or openings 57 formed therein and longitudinally spaced projecting pins or studs 58 and 59 which are arranged slightly off center with relation to a longitudinal central line running through the face of the plate 56. The pin or stud 59 adjacent the lower end of the plate 56 is provided with a flat side or face 60, see Figs. 4 and 5. It will be understood that the striker device 55 is mounted upon the face of a door pillar or jamb 61 adjacent

the latch mechanism 35 by passing screws or bolts (not shown) through the openings in the base plate 56 and is located in a position so that the flat free end 42a of the latch member or element 42 will engage the adjacent flat side or face 60 of the stud or pin 59 of the striker in flatwise relation as shown in Fig. 4 when the door B is fully closed. A preliminary or safety latching position of the door is provided by virtue of the notched lower edge of the latch member or element 42 which provides the stop or abutment 42b which, as the latch assembly and combined wedge member or dovetail 35 is moved inwardly between the vertically spaced pins or studs 58 and 59, will first engage the flat face or side 60 of the pin 59. Upon further movement of the door B towards closed position, the tension spring 50 will force the latch into its fully operative or final locking position, thus bringing the flat free end 42a thereof into engagement with the adjacent flat surface or face 60 of the pin 59.

As seen in Fig. 4, the adjustable screw or stud 44 has been adjusted so as to cause the spring-like plate member or cover 45 of the latch assembly to engage the adjacent striker pin 51. If the pressure or tension is too great, it will be understood that the screw 44 can be adjusted so as to release some of its pressure upon the plate 45. The adjustment may be effected in such a manner as to cause a relatively tight, non-rattling fit between the latch assembly 35 and the striker element 55 so as to prevent the door from rattling.

As stated above, the latch element or member 42 may be released from its latching position either by operating the outside door handle E or by the remote control mechanism F located on the inner face of the door B. As seen in Fig. 2, the door handle E is provided with a shank 9 of square or rectangular cross section. The shank of the handle is adapted to be passed through an opening in the outer panel of door B and to enter the squared recess or socket 14b formed in the embossment 14a of the rollback device 14. The rollback 14 is adapted to be maintained in position upon the case plate portion 10 by virtue of the fact that its embossment or extension 14a fits within a circular or round recess or hole formed in the case plate member 10 and additionally by means of a bracket located at the inner face of the case plate. This bracket, as shown, comprises a base portion 65 which is preferably welded to the inner face of the flange 11 and with an offset or angularly disposed portion 66 which extends substantially parallel to the inner face of the base portion 10 of the case plate and is spaced therefrom so as to engage the adjacent face of the rollback 14. The portion 66 is provided with a round or circular opening 67 (see Fig. 3) through which the shank 9 of the handle extends. It will be understood that by turning the handle E in a clockwise direction as viewed in the drawings, the rollback 14 will be caused to pivot about its embossment portion or bearing 14a and to shift the control lever or link member 20 in a clockwise direction about its pivot 21 against the action of the flat tension spring 39. Such movement of the lever 20 will cause its offset lower end portion 25 to move upwardly and to force the latch pin 46 upwardly in its slots and thus retract the latch member or element 42 and cause it to move into its position within the socket 41. Immediately the handle E is released, the spring 39 tends to return the lever 20 and the rollback 14 to their original positions, thus allowing the tension spring

50 to again project the latch until it assumes its latching position as shown in Fig. 4.

The remote control device for retracting the latch member or element 42 is shown as a whole at F in Fig. 8. As shown, this remote control device comprises a mounting plate 70 having attached thereto a strap-like member 71 which provides, with the plate 70, a housing or cage for a cam member or actuator 72. This cam member 72 is rigidly mounted upon a short shaft or stud 73 which finds a bearing in the strap member 71 and which extends through and is journaled in an opening formed in the plate 70. It will be understood that the inner end of the shaft or stud 73 projects beyond the inner face of the door B and is of preferably squared section to receive and support a conventional inner actuating handle M, Fig. 1. The cam member 72 is provided with a notch or recess 74 with which a hump or bend 75a of a tension spring 75 engages when the member 72 is in its substantially vertical position as shown. The tension spring 75 contacts the members 71 and 72 and is so formed and shaped to maintain its hump portion 75a in constant contact with the adjacent surface or edge of the cam member 72. When the parts are in the position of Fig. 8, it will be noted that the spring 75 is in engagement with the recess or notch 74 in the cam member 72 for the purpose of maintaining said cam member in its upright or vertical position. When, however, the cam member 72 is shifted to the left of Fig. 8, the hump 75a enters a second notch 74a in the cam to hold said cam in an angular tilted position toward the left, which position is not shown. When in this latter position, a lug or projection 72a engages the member 71 to prevent further tilting movement of the cam toward the left.

The upper end of the cam member 72 is pivotally connected at 76 to a connecting link or member, shown as a whole at 77. As shown, the opposite end of the link 77 is provided with an elongate longitudinally extending slot 78 and with an inturned lug or projecting portion 79, see particularly Figs. 3 and 6. The actuator or rollback 14, see particularly Figs. 3, 6 and 7, is provided with a stud having a fixed substantially rectangular head portion 80. This stud projects from the inner face of the rollback. The headed stud 80 is adapted to be engaged with the slot 78 so as to support the adjacent end of the link or bar 77. When the link is assembled with the stud 80, the projecting lug 79 carried by said link is aligned with the slot 77 formed in the upper adjacent portion of the rollback and can move into said slot when the link is shifted toward the left of Figs. 3, 6 and 8. Thus, when the link 77 is in its broken line position as shown in Fig. 3, the lug 79 underlies the nose portion 13 of the rollback member 14 and prevents said rollback from being swung or shifted in a clockwise direction upon actuation of the outer door handle E. In other words, the remote control device F serves as a lock operable from the inside of the car body as well as means for actuating the rollback 14, as well as means for actuating the rollback 14, control lever 20 and the latch assembly 35 to release the latch member or element 42.

I claim:

1. In a latch assembly adapted to be mounted on a swinging door, a mounting plate having an angularly disposed flange located at an edge thereof, a dovetail mounted upon said flange and having a recess at one face thereof, a latch mem-

ber conforming substantially to the shape of said recess and pivoted therein adjacent the leading end of the dovetail, tension means for maintaining said latch member normally in latching position, and means for actuating the latch member to retract the same.

2. In a latch assembly adapted to be mounted on a swinging door, a mounting plate, a dovetail mounted upon said plate and including a body having an inclined face, a spring member secured at its forward end to said face and having its rear end movable relative thereto, and means for adjusting said rear end to change the contour of the working face of the dovetail.

3. A door dovetail comprising a wedge-shaped member, a relatively thin spring member fixed upon the face of the member and adjustable into fixed positions to vary the wedge-shaped contour of the member, and means for adjusting said spring member.

4. In a dovetail having a wedge-shaped body portion, a member secured to an exterior face of the body portion and forming a portion of the exterior wedge-shaped contour of said body portion, means for adjusting said member relative to said body portion and independently thereof to change said contour, said member having a notch in another face thereof, and a latch member substantially fitting said notch and pivotally mounted to swing into and out of the same.

5. In a latch assembly adapted to be mounted on a swinging door, a mounting plate, a dovetail mounted upon said plate and having a recess at one face thereof, a latch member pivoted within said recess to swing up and down about an axis extending transverse to the direction of swinging of the door, tension means for maintaining said latch member normally in latching position, and means for retracting said latch member.

6. In a latch assembly adapted to be mounted on a swinging door, a mounting plate, a dovetail mounted upon said plate and having a recess at one face thereof, a latch member pivoted within said recess to swing up and down about an axis extending transverse to the direction of swinging of the door, said latch member conforming substantially to the shape of said recess and having a stepped formation providing two locking steps, tension means for maintaining said latch member normally in latching position, and means for retracting said latch member.

7. In a latch assembly adapted to be mounted on a swinging door, a mounting plate, a wedge-shaped dovetail mounted upon said plate, a member secured to said dovetail and forming a portion of the exterior wedge-shaped contour of the dovetail, and means for adjusting said member relatively to and independently of said dovetail to change said contour.

8. In a dovetail having a body portion, a member secured to the body portion and forming an exterior inclined working face for said body portion, and means on said body portion for shifting said member relative to said body portion to change the operative position of said working face.

9. In a dovetail having a body portion, a spring member secured to the body portion and forming an exterior inclined working face for said body portion, and means on said body portion for shifting said member relative to said body portion to change the operative position of said working face.

WILLIAM MARSHALL.
